CLAIM

The ornamental design for a display panel with graphical user interface, as shown and described.

DESCRIPTION

FIG. 1 is a front view of a first image in a sequence of a display panel with graphical user interface showing our new design;

FIG. 2 is a front view of a second image thereof;

FIG. 3 is a front view of a third image thereof;
FIG. 4 is another view of FIG. 1, but shown without the broken lines depicting portions of the graphical user interface, for clarity of illustrating the claimed design;

FIG. 5 is another view of FIG. 2, but shown without the broken lines depicting portions of the graphical user interface, for clarity of illustrating the claimed design; and,
FIG. 6 is another view of FIG. 3, but shown without the broken lines depicting portions of the graphical user interface, for clarity of illustrating the claimed design.

The appearance of the display panel with graphical user interface sequentially transitions between the images shown within FIGS. 1-3 and FIGS. 4-6. The process or period in which an image sequence transitions from one image to another image forms no part of the claimed design.

The outermost broken lines in FIGS. 1-6 depict a display panel and form no part of the claimed design. The remaining broken lines in FIGS. 1-3 depict portions of the display panel with graphical user interface that form no part of the claimed design.
